UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

VALVE CONSTRUCTION FOR PNEUMATIC TOOLS.

Application filed July 25, 1921. Serial No. 487,356.

To all whom it may concern:

Be it known that I, EDWARD W. STEVENS, a citizen of the United States of America, residing at Detroit, in the county of Wayne 5 and State of Michigan, have invented certain new and useful Improvements in Valve Constructions for Pneumatic Tools, of which the following is a specification, reference being had therein to the accompanying drawings.

The invention relates to pneumatic tools of that type in which the valve is in the form of a sleeve through which the piston reciprocates and in which the shifting of 15 the valve is effected by the pressure of trapped fluid compressed by the piston in its return stroke. With such type of construction it is highly important to avoid leakage, tending to neutralize the differential 20 pressure and thereby interfering with the quick and positive shifting of the valve. This is not difficult to attain when the construction is new, but the wear incident to use enlarges the clearances and destroys the 25 proper balance. I have therefore devised a construction which is not so dependent upon close clearances and will remain operative after the working surfaces are worn.

In the drawings:

30 Figure 1 is a central longitudinal section through the tool in one position of the piston and valve;

Figure 2 is a similar view of the piston and valve in different positions;

35 Figure 3 is a longitudinal section in a plane indicated by line 3-3 of Figure 1.

A is the casing or barrel of the tool containing the reciprocating piston B. C is the sleeve valve surrounding the piston and D 40 is a cylindrical valve casing engaging a counterbore in the main barrel. The valve C has a tubular body portion, the internal diameter of which corresponds to that of the barrel. The opposite end portions of 45 this tube slidably fit the portions E and E' of the casing D, which are of corresponding diameter, and intermediate these end portions are the pairs of outwardly projecting annular flanges F, F', G, G', respectively 50 slidably engaging portions H and I of the casing, the portion I being of greater diameter than the portion H. Adjacent to the flange F on the outer side thereof are a series of fine ports J extending through the 55 sleeve and between the flanges G and G' are

a series of large ports K. The casing D is further provided with a series of annular ports L, M and N, the first surrounding the portion E and the others surrounding the portion I. The port L is connected with 60 the supply passages O for the motive fluid, which extend longitudinally through the walls of the casing D intersecting said port L. The port M is connected by a passage P with the outer end of the barrel and the port N is connected with an exhaust passage Q. The casing is further provided with the passages R, S and T. The passage R leads from the supply passage O to a port in the portion H. The passage S leads from 70 the end of the portion I to a port S' in the barrel, which is controlled by the movement of the piston, and the passage T communicates with the portion I of the barrel intermediate its end and the channel N and 75 connects with the supply passage O.

With the construction as thus far described, when the valve is in the position shown in Figure 1, live air from the supply 80 passages will pass through the annular port L into the barrel, driving the piston forward or towards the tool, while the air which is in front of the piston is exhausted through the passage P, channels M and N and exhaust port Q. When the piston has 85 over-ridden the port S', air from the barrel passing through said port and the passage S' will develop a pressure upon the lower face of the flange G' and as this area is in excess of the area of the flange F, the valve will be 90 shifted rearward. This will register the groove N between the flanges G and G' with the exhaust port Q, permitting the exhausting 95 of the pressure above the piston in the barrel through the ports K. The shifting of the valve also moves the flange G' above the port T so that when the pressure in the barrel drops, the pressure operating against the flange G' is still maintained by live air entering through the port T. The valve in 100 its shifted position, or as shown in Fig. 2, opens communication between the passage R and the channel M, thereby permitting the air to pass through the passage P below the piston to cause the return of the same. The 105 valve maintains this position until in the return stroke of the piston the exhaust ports K are sealed and the air which is trapped above the piston is compressed. This highly compressed air passes through the small 110

- ports J to the upper side of the flange F and while the area of this flange is less than the area of the flange G', the higher fluid pressure on the flange F will overcome the lower fluid pressure on the flange G' and shift the valve.
- The construction as above described has heretofore been used, but I have devised certain improvements which are as follows:
- 10 1. One improved feature in the arrangement of a by-pass or air channel U leading from the upper end of the barrel to a port U' adjacent to the flange F. Another feature is the placing of a constantly open but restricted port V between the air supply and the upper end of the barrel, it being usual to place such a port directly adjacent to the flange F. With such construction, when the valve is in position shown in Figure 2 and while the piston is on its upward stroke and before it has sealed the exhaust ports K, the channel U and port U' supplement the ports J in exhausting the air which may leak from the port E between the valve sleeve and its casing. This avoids building up pressure on the flange F so that even where there is leakage from the other end of the valve sleeve, the pressure acting upon the flange G' will still be in excess of the pressure acting upon the flange F. Another advantage of the construction is that highly compressed air which is trapped in the upper end of the barrel is bypassed through the channel U and port U' to build up pressure upon the flange F for shifting the valve. Still another advantage is that by dispensing with the constantly open port leading to the flange F, the ports J and U' need to take care only of the air leaking about the valve sleeve and are relieved from the necessity of exhausting air from said constantly open port. The total effect is to provide a valve of exceptionally quick and positive response and one which will remain operative after long service.
  - 15 2. The combination with a reciprocating piston, a barrel therefor and a sleeve valve surrounding and fitting said piston and slidably engaging a recess in said barrel, annular flanges of different diameters surrounding said valve and engaging portions of said recess of corresponding diameters, smaller of said flanges with the rear end of the barrel to transfer thereto the trapped fluid compressed by the piston in its rearward stroke while said restricted exhaust ports are sealed thereby, and also constituting an auxiliary exhaust for leakage into said recess when the pressure within the barrel is exhausted.
  - 20 3. The combination with a reciprocating piston, a barrel therefor and a sleeve valve surrounding and fitting said piston and slidably engaging a recess in said barrel, annular flanges of different diameters surrounding said valve and engaging portions of said recess of corresponding diameters, main exhaust ports through said valve cooperating with an exhaust port in the barrel, an air supply port to the barrel controlled by a portion of said valve, restricted exhaust ports through said valve adjacent to the flange of smaller diameter for exhausting leakage from said supply port to the recess engaged by said flange, and a channel connecting the portion of the recess engaged by said last-mentioned flange with the end of the barrel for transferring the trapped fluid compressed by the piston while said restricted exhaust ports are sealed and for exhausting the leakage to said recess when the connected portion of said barrel is open to the main exhaust.
  - 25 4. The combination with a reciprocating piston, a barrel therefor and a sleeve valve surrounding and fitting said piston and slidably engaging a recess in said barrel, an annular supply port for said barrel alternately opened thereto and sealed by a portion of the valve, an annular flange surrounding the valve engaging a portion of the recess of corresponding diameter, restricted exhaust ports through said valve adjacent to said annular flange for exhausting the leakage from said supply port into said recess while the pressure in the communicating portion of the barrel is exhausted, and a channel connecting the portion of the recess adjacent to said flange with the end of the barrel for the transfer of fluid compressed by the piston while said restricted exhaust ports are sealed thereby and for forming an auxiliary exhaust for leakage into said recess while the pressure in the connected portion of the barrel is exhausted.
  - 30 5. The combination with a reciprocating piston, a barrel therefor and a sleeve valve surrounding and fitting said piston and slidably engaging a recess in said barrel, an annular pressure supply port for said barrel alternately covered and uncovered by a portion of said valve, an annular flange surrounding said valve and engaging a portion of said recess of corresponding diameter, restricted exhaust ports through said valve adjacent to said flange for exhaust leakage to said recess from said annular

- supply port, a channel connecting said recess with the end of said barrel for transferring the trapped fluid compressed by the piston to produce a shifting pressure for the valve, 5 said channel also constituting an auxiliary exhaust for leakage pressure when the pressure in the connected portion of the barrel is exhausted, and a leak port from the supply pressure to said end portion of the 10 barrel for building up starting pressure.
5. The combination of a barrel having a piston chamber, a piston reciprocating therein, a reciprocating sleeve valve defining a part of said piston chamber and 15 governing the admission and exhaust of the motive fluid for reciprocating the piston, said valve being operated in one direction by motive fluid compressed by the piston in the rear end of the piston chamber on its return 20 stroke and having an external pressure area, and means for by-passing such fluid compressed by the piston and discharging it against such pressure area.
6. The combination of a barrel, a piston reciprocating therein, a sleeve valve surrounding said piston and forming a portion 25
- of said barrel, said valve controlling the admission and exhaust of the motive fluid for reciprocating the piston, opposed differential areas on said valve, and means for 30 subjecting said differential areas to fluid pressures derived from opposite ends of the barrel including a by-pass to the smaller area for the fluid compressed by the piston in its return stroke. 35
7. The combination of a barrel, a piston reciprocating therein, a reciprocating valve governing the admission and exhaust of motive fluid for reciprocating the piston and operated in one direction by motive fluid 40 compressed by the piston on its return stroke in the rear end of the barrel, said valve having an external pressure area, means for by-passing such fluid compressed by the piston and discharging it against such pressure area, a fluid supply passage, and a constantly open restricted port between said fluid supply passage and the end of said barrel in which the fluid is compressed. 45

In testimony whereof I affix my signature. 50

EDWARD W. STEVENS.
